IRONER

George W. Wardwell, Jr., Nichols, Conn., assignor
to General Electric Company, a corporation of
New York

Application December 21, 1937, Serial No. 181,012

15 Claims. (Cl. 33—59)

The present invention relates to ironers of the type having ironing members comprising a roll and a cooperating shoe.

The object of my invention is to provide an improved construction and arrangement in ironers of this type, and for a consideration of what I believe to be novel and my invention, attention is directed to the following description and the claims appended thereto.

In the accompanying drawings, Fig. 1 is a perspective view of an ironer embodying my invention; Fig. 2 is an end view of the ironer, partly broken away to show the driving mechanism; Fig. 3 is a sectional view taken on line 3—3 of Fig. 2; Fig. 4 is an end elevation partly in section; Fig. 5 is a sectional view taken on line 5—5 of Fig. 4; Fig. 6 is a perspective view of one of the speed changing gears for driving the ironer roll; Fig. 7 is a front elevation of the shifting member for changing the ironer roll speed; Fig. 8 is a sectional elevation taken on line 8—8 of Fig. 2; Fig. 9 is a sectional view taken on line 9—9 of Fig. 8; Fig. 10 is a sectional view taken on line 10—10 of Fig. 8; Fig. 11 is an exploded view of the clutch which controls the movement of the roll toward and away from the shoe; Fig. 12 is a perspective view of the trip member controlling the clutch; Fig. 13 is a diagrammatic view of the knee pad operated linkage for operating the trip member; Fig. 14 is an end view, partly broken away, of the construction for supporting the shoe; Fig. 15 is a top plan view, partly broken away, of the construction for supporting the shoe; and Figs. 16, 17 and 18 are perspective views of parts of the shoe supporting mechanism.

Referring to the drawings, there is shown an ironer having a shoe 1 and a roll 2 which are supported by a housing 3 containing the mechanism for rotating the roll and for moving the roll toward and away from the shoe. The housing is provided with a flange 4 which rests on and is suitably secured to the top 5 of a suitable table.

The shoe comprises an arcuate metal plate 6 which is heated by suitable electrical heating elements (not shown). On the upper surface of the plate are secured lugs 7 to which are fixed the edges of a cover plate 8. At the center of the shoe (Fig. 8) is a bracket 9 fixed to the upper surface of the plate 6. Integral with the bracket 9 is a sleeve 10 which slidably and rotatably fits over the end of a rod 11. The sleeve 10 has a loose fit on the rod, permitting tilting movement with reference to the rod about an axis perpendicular to the rod so that the shoe

can be aligned with the roll. In the outer end of the sleeve 10 are notches 12 which receive a pin 13 fixed in the rod 11. The shoe is urged to the right, as viewed in Fig. 8, by a compression spring 14 arranged between a washer 15 and the bracket 9. The spring 14 holds the notches 12 against the pin 13 and resiliently centers the shoe on the arm 11. The notches 12 have inclined sides so that the shoe may turn about the rod 11 so as to provide uniform pressure between the shoe and the roll throughout the width of the shoe. This turning movement is yieldingly resisted by the compression spring 14. The inclined sides of the notches are in effect cam surfaces. By exerting a twisting force on the shoe in a clockwise direction as viewed in Fig. 2, the notches 12 may be moved clear of the pin 13 in which case the shoe may be further pivoted about the rod 11. A shoulder 12a prevents twisting of the shoe in the reverse direction.

At the right end of the shoe is a leaf spring 16, one end of which is bolted to the upper surface of the plate 6 and the other end of which bears against the under side of the rod 11 pivoting the shoe about the pin 13 in a clockwise direction to the position shown in Fig. 8 in which the rod 11 rests against the upper edge of an elongated flanged opening 17 in the shoe cover. This holds the shoe steady while the shoe and roll are separated. This pivotal movement is permitted by the clearance between the sleeve 10 and the rod 11.

When the shoe and roll are in engagement, the pressure therebetween causes the rod 11 to deflect. The strength of the rod is such that it serves to limit the pressure between the roll and the shoe and therefore to decrease the variations in pressure due to variations in the thickness of the material being ironed and of the pad. The mounting of the shoe also permits movement of the shoe to equalize the pressure throughout the surface of the shoe. The leaf spring 16 is relatively light compared to the pressure between the roll and shoe to the ironing, and, accordingly, has substantially no effect on the tilting movement of the shoe required to equalize the pressure throughout the length of the shoe.

The above-described arrangement provides for tilting movement of the shoe about two axes; (1), tilting movement about the pin 13, i. e. about an axis perpendicular to the plane of the drawing in Fig. 8, and (2) a turning about the rod 11, i. e. about an axis in the plane of the drawing. It is, therefore, obvious that the pressure between

the roll and the shoe will be equalized throughout the surface of the shoe.

The right-hand end of the rod 11 (Fig. 8) is fixed in bosses 18, 19 and 20 of hinge member 21 which is hinged to the ironer housing 3 by means of a pin 22. The member 21 has hinge lugs 23, 24 and 25 which pivot on the pin 22. The pin is threaded into a boss 25a in the end wall of the housing 3 and extends through hinge lugs 26, 27 and 28 integral with the ironer housing. Hinged on the pin 22 is a hinge member 29 having a hinge lug 30 located between the lugs 24 and 25. On the upper surface of the hinge member 29 is a seat 31 for the lower end of a coil spring 32. The upper end of the coil spring presses against the head of a bolt 33 which is threaded into a boss 34 on a web 35 extending across the ironer housing (Fig. 4). The hinge member 29 is provided with an elongated clearance opening 36 around the bolt 33. With this arrangement, it is obvious that the member 29 is yieldingly held against the upper surface of the boss 34 by the spring 32. The hinge members 21 and 29 are connected together by a pin 37 which slidably and rotatably extends through lugs 38 and 39 on the member 29 into an opening 40 in a lug 41 on the member 21. The outer end of the pin 37 projects through an elongated slot 42 in the end wall of the ironer housing and on the projecting end of the pin is pinned a handle 43.

When the end of the pin 37 fits in the opening 40 in the lug 41 the members 21 and 29 are rigidly connected together. While so connected the pressure between the roll and the shoe is limited by the coil spring 32. That is, the hinge members 21 and 29 pivot about the pin 22 as a unit in a clockwise direction, as viewed in Fig. 4, until the pressure between the roll and the shoe is balanced by the pressure exerted on the hinge member 29 by the coil spring 32. The slot 42 provides sufficient clearance to permit this movement.

Between the lugs 38 and 39 of the hinge member 29 is a cam 44 which is pinned to the pin 37. In the side of the cam facing the lug 39 is a notch 45 into which fits a pin 46 fixed in the lug 39. One side 47 of the notch 45 is inclined, as shown in Figs. 14 and 18, providing a cam surface cooperating with the pin 46 which causes the pin 37 to be moved out of the opening 40 when the handle 43 is turned in a clockwise direction, as viewed in Fig. 14. When the pin is moved clear of the opening 40, the hinge member 21 is no longer connected to the hinge member 29 and the shoe can, accordingly, be pivoted about the pin 22 away from the roll. The cam 44 is provided with a surface 48 which bears against the under side of the boss 19 on the hinge member and lifts the hinge member after the pin 37 is moved clear of the opening 40. Pivotal movement of the cam 44 is limited by stops 44a and 44b. The movement of the hinge member 21 is limited by the engagement of a stop 49 with a cooperating stop 50 on the ironer housing (Fig. 4). The separation between the roll and shoe permitted by this pivotal movement of this hinge member 21 is sufficient to expose the surface of the shoe for cleaning purposes. Further exposure of the shoe may be obtained by forcibly turning the shoe backwards as viewed in Fig. 8, until the notches 12 are clear of the pin 13. The shoe may then be pivoted about the rod 11 until the face of the shoe is turned upward exposing

the entire surface of the shoe for cleaning and waxing.

The construction described above serves as an emergency release for separating the roll and shoe in case the power supply fails while the roll and shoe are in engagement.

The roll (Fig. 8) comprises a sheet metal cylinder 51 on the outer surface of which is a pad 52 held in place by a pad cover 53. The pad cover is held on the roll by means of snap rings 54 which fit in grooves 55 in the inner surface of the cylinder 51 within each end of the roll. Slightly to the right of the center of the roll, as viewed in Fig. 8, is a bearing 56 which rotatably supports the roll on an eccentric 57. Endwise movement of the roll off the eccentric is prevented by a washer 57a fixed to the eccentric. Integral with the bearing 56 is an outwardly extending flange 58 to which is riveted the inner edge of a flexible sheet steel diaphragm 59. The outer edge of the diaphragm is riveted between inwardly extending flanges 60 and 61 integral with rings 62 and 63 which are suitably secured to the inside of the cylinder 51, for example by bolts 64. Integral with the flange 58 of the bearing 56 are radially projecting arms 65 opposite radial slots 66 in the diaphragm 59. Integral with the arms 65 are flanges 67 (Fig. 9) which project beyond the edges of the slots 66 on one side of the diaphragm and flanges 68 (Fig. 10) which project beyond the edges of the diaphragm on the opposite side of the slots 66. The flanges 67 and 68 are connected by a web 69 (Fig. 8) which projects through the center of the slots 66. The flanges 67 and 68 are spaced apart to permit flexure of the diaphragm, thus providing a tiltable mounting for the roll. As shown in Fig. 8, the spacing of the flanges 67 and 68 increases radially outward from the bearing 56, the shape of the flanges conforming to the shape of the diaphragm when the roll is tilted. Under normal conditions, the diaphragm does not touch the flanges. The flanges merely serve as stops, limiting the tilting of the roll and preventing damage of the diaphragm. Such damage might result from an attempt to pick up the ironer by taking hold of the outer end of the roll. In this event, the diaphragm would be lifted until it came into contact with the flanges.

The eccentric 57 is pinned to the projecting end of the shaft 70 which is journaled in a bearing 71 in the outer end of a tube 72 fixed in a boss 73 in the side walls of the ironer housing. When the eccentric 57 is rotated the ironer roll is moved thereby toward and away from the shoe. When the eccentric is in the position shown in Fig. 8 the roll is separated from the shoe and when the eccentric is turned through 120° the roll is pressed against the shoe.

If the bearing 56 rested directly on the outer surface of the eccentric 57, rotation of the eccentric would cause rotation of the roll due to the friction between the eccentric and bearing. To prevent this rotation of the roll, an intermediate sleeve 74 is arranged between the outer surface of the eccentric and the inner surface of the bearing. Integral with the inner end of the sleeve 74 are outwardly extending tabs 74a (Fig. 10) which are fixed to a plate 75 having forked ends 75a straddling the sleeve 74 and an upstanding portion 75b having flanges 76 which extend on each side of a tongue 77 on a bracket 78 fixed to the tube 72. The flanges 76 cooperate with the tongue 77 to prevent rotation on the sleeve 74 upon rotation of the eccentric. The

bearing 56, which rests on the outer surface of the sleeve 74, accordingly follows the movement of the sleeve rather than the turning movement of the eccentric 57.

As the eccentric is turned the movement of the sleeve 74, and therefore the movement of the roll, can best be described as a pivotal movement about the tongue 77 of the bracket 78. During the operation of the ironer the eccentric is turned by the shaft 70, in a manner which will hereinafter be described, in a counterclockwise direction, as viewed in Fig. 2. During the first quarter revolution of the shaft from the position shown in Fig. 8 the eccentric is rotated through 90° moving the sleeve 74 to the right of a center line connecting the shoe and the shaft 70, as viewed in Fig. 2. During the second quarter revolution, the sleeve is swung back into line with the center line connecting the shaft 70 and the shoe. The roll follows the movement of the sleeve until it contacts the shoe, after which the friction between the roll and the shoe is greater than the friction between the roll bearing 56 and the sleeve 74.

From the point of view of the operator, as the roll moves toward the shoe it first moves downward and at the same time turns backward. This continues during the first quarter revolution of the eccentric. During the second quarter revolution of the eccentric, the roll moves upward and at the same time turns forward until it occupies the same angular position it had when away from the roll. When the roll moves away from the shoe the roll appears to first raise and then lower to its final position. With the above described construction, the material arranged on the roll in effect is brought directly into contact with the shoe without any net turning of the roll. If the sleeve 74 were omitted, the roll would turn with the eccentric. This would mean that the roll would turn a half revolution while moving toward the shoe, advancing the material on the roll with reference to the shoe through one-half the circumference of the roll. This would bring the front part of the material beyond the shoe with reference to the rotation of the roll so that this part of the material would not be ironed.

In the right end of the roll is an internal gear 79 which is fixed to the inner surface of the cylinder 51 by screws 80. When the roll is separated from the shoe, as shown in Fig. 8, the teeth of the internal gear are separated from the teeth of a pinion 81 which is continuously driven in a manner hereinafter described. When the roll is pressed against the shoe the internal gear is moved into mesh with the pinion 81 completing a driving connection to the roll. This driving connection is completed before full ironing pressure is developed between the roll and the shoe, thereby decreasing the load on the gear teeth.

As the internal gear is moved into mesh with the pinion, there is some tendency for clashing of the gear teeth. This tendency is increased by the fact that the gear 79 is an internal gear, with its teeth extending radially inward, while the pinion 81 is an external gear, with its teeth extending radially outward. It is, therefore, possible for the tips of a pair of teeth on the pinion 81 to straddle the pair of teeth on the internal gear 79. Under this condition, further movement of the internal gear toward the pinion would cause serious jamming of the gear teeth. This tendency for jamming of the gear teeth is prevented by the tiltable mounting of the

roll provided by the flexible diaphragm 59. This tiltable mounting permits the internal gear 79 to pause in its movement toward the pinion 81 until the teeth on the continuously rotated pinion 81 have turned to a position permitting non-clashing engagement of the gear teeth. The movement of the gear teeth to the non-clashing position is also assisted by the slight turning of the roll due to its following the movement of the sleeve 74. Since the eccentric is being continuously turned, the pause in the movement of the internal gear 79 results in a tilting movement of the roll. That is, while the right end of the roll pauses, the left end of the roll moves toward the shoe at a greater rate.

Since the bearing 56 and diaphragm 59, which rotatably support the roll, are located to the right of the center of the roll, as viewed in Fig. 8, the pressure exerted on the roll by the shoe tends to pivot the roll about the bearing 56 in a counterclockwise direction an axis perpendicular to the plane of Fig. 8. This movement of the roll tends to move the teeth of the gear toward the teeth of the pinion 81. This movement is limited by the engagement of a flange 82 on the internal gear with a collar 83 on the shaft 84 to which the pinion is fixed. The collar 83 and the flange 82 have the same diameter as the pitch circles of the pinion 81 and the internal gear 79, respectively, so that when these parts are in engagement the gear teeth mesh on their pitch circles.

The ironer is driven by an electric motor 85 (Fig. 2) mounted within the lower portion of the ironer housing 3. The motor shaft 86 is journaled in a boss 87 in a web 88 which extends across the side walls of the ironer housing. The side and top walls of the ironer housing and the webs 88 and 35 provide an enclosure for the driving mechanism of the ironer. On the upper end of the motor shaft 86 is cut a worm 89 which meshes with a worm gear 90 loose on a reduced portion 91 of the shaft 70. Integral with the hub of the worm gear 90 are gears 92 and 93 which mesh, respectively, with gears 94 and 95 loose on the shaft 84. The gears 94 and 95 are urged apart by a compression spring 96 against the flanges 97 of a shifting member 98. The upper end of the shifting member is pivoted at 99 (Fig. 7) on a bracket 100 fixed to the end wall 50 of the ironer housing. In the lower end of the shifting member is an elongated slot 101 in which fits a crank pin 102 integral with a shaft 103. The shaft 103 journaled in the front wall of the ironer housing and on its outer end has fixed thereto a handle 104. The handle is held against the front face of the ironer housing by a compression spring 105 arranged between a flange 106 integral with the shaft 103 and a packing washer 107 pressed by the spring against the inner surface of the ironer housing. The spring 105 resiliently holds the handle against detents 108 on the outer surface of the ironer housing.

When the handle 104 is in the position shown in Fig. 1 the shifting member 98 is in the position shown in Fig. 5 in which the gears 94 and 95 are loose on the shaft 84, the shaft accordingly being stationary. When the lower end of the handle 104 is moved to the left, as viewed in Fig. 1, the shifting member 98 is moved to the right, as viewed in Fig. 5, bringing the clutch teeth 109 on the gear 95 into engagement with a clutch key 110 fixed to the end of the shaft 84. The gear 95 rotates in a clockwise direction, as viewed in Fig. 6. The ends of the clutch teeth 109 are tapered to facilitate engagement with the

key 110. In this position the shaft 84 is rotated at its highest speed.

When the lower end of the handle 104 is moved to the right, as viewed in Fig. 1, the shifting member 98 is moved to the left, moving the clutch teeth 111 in the gear 94 into engagement with a clutch key 112 fixed in the shaft 84. This couples the gear 94 to the shaft 84 and causes the shaft 84 to be driven at its lowest speed. The clutch teeth 111 and clutch key 112 are similar to the clutch 109 and the clutch key 110.

With the above described arrangement, the speed of rotation of the ironer roll can be changed or stopped while the roll is rotating.

The rotation of the shaft 70 in 180° steps, which causes the roll to be moved toward and away from the shoe, is accomplished by means of a clutch having an arm 113 pinned to the outer end of the reduced portion 91 of the shaft 70, the arm having a longitudinal slot 114 in its outer face in which is slidably carried a clutch key 115. The clutch key is confined in the slot by a plate 116 which is pinned to the outer surface of the arm 113 by pins 117. In the center of the plate 116 is an elongated slot 118 in which is slidably carried a sleeve 119 having outwardly extending flanges 120 and 121 on opposite sides of the plate 116. Loosely projecting within the sleeve 119 is a tongue 122 on the clutch key 115. Arranged between the sleeve 119 and an arm 123 of a trip lever 124 is a tension spring 125 (Figs. 2 and 3). As is obvious from Figs. 2 and 3, the tension spring pulls the clutch key downward against the upper surface of the arm 123. In this position the clutch key is disconnected from the worm gear 90 and the shaft 70 is stationary.

The trip lever 124 is pinned to the upper end of a shaft 126 rotatably carried in a boss 127 (Fig. 2) in the web 88 of the ironer housing. The lower end of the shaft 126 has fixed thereto a crank arm 128 which is connected by a link 129 to a lever 130 pivoted at 131 on the under side of the ironer table. The lever 130 is urged by a spring 132a against a stop 132. On the outer end of the lever is a knee pad 133.

When the knee pad is moved in the direction of the arrow 134, of Fig. 13, the trip lever 124 is moved in the direction of the arrow 135, moving the trip lever clear of the adjacent end of the clutch key 115. The adjacent end of the clutch key is now moved downward by the tension spring 125 into engagement with one of the notches 136 in a flange 137 on the continuously driven worm gear 90. This establishes a driving connection from the worm gear 90 to the shaft 70 causing the rotation of the shaft in a counterclockwise direction as viewed in Fig. 2. Once the driving connection is established, the knee pad 133 may be released and it will be returned to the position shown in Fig. 13 by the spring 131. This also returns the trip lever 124 to the position shown in Fig. 3. During the first quarter revolution of the shaft 70, the spring 125 acts in the direction to move the clutch key into engagement with one of the notches 136. During the second quarter revolution of the shaft 70 the spring acts in the direction to pull the clutch key out of engagement with the notches 136. This is due to the fact that the clutch key rotates with respect to the sleeve 119 and that the spring 125 always exerts a downward pressure on the sleeve 119. The clutch key is not moved out of engagement with the notches 136 by the spring 125 since due in part to the fact that the spring is not strong enough and in part to the fact that the

leverage exerted by the spring is a minimum when the arm 113 is at right angles to the line of action of the spring. As the shaft nears the completion of its second quarter revolution the tongue 138 on the end of the clutch key 115 opposite the end which is in engagement with the worm gear 90, passes between a projection 139 and a cam surface 140 on the trip lever. The projection 139 is shaped to prevent movement of the clutch key out of the notch 136 by the spring 125 until the completion of the second quarter revolution of the shaft. The cam surface 140 is shaped so that at the end of the second quarter revolution of the shaft 70 the clutch key is forcibly moved out of the notch 136. Once out of the notch 136 the clutch key is further moved downward against the trip lever 123 by the spring 125, thus separating the clutch key from the notches 136. Due to the increasing effectiveness of the spring 125 as the key moves toward its line of action, the spring may have sufficient effect to move the key out of the notch at the completion of the second quarter revolution of the shaft 70.

What I claim as new and desire to secure by Letters Patent of the United States is:

1. In an ironer, a roll, a shoe, motor driven mechanism for driving the roll and for effecting engagement and separation of the roll and shoe, a shoe supporting member, a second member, a frame, means supporting said members on said frame for movement relative to the frame and to each other, a pin slidably carried by said second member and movable into and out of engagement with the shoe supporting member for releasably coupling said members, and means including a spring connected between said second member and said frame for limiting the pressure between the roll and the shoe.

2. In an ironer, a roll, a shoe, motor driven mechanism for driving the roll and for effecting engagement and separation of the roll and shoe, a shoe supporting member, a second member, a frame, means supporting said members on said frame for movement relative to the frame and to each other, a pin slidably and rotatably carried in said second member for releasably coupling said members, cam means on the pin and operable upon rotation thereof for moving the pin axially to a position uncoupling said members, and means including a spring connected between said second member and said frame for limiting the pressure between the roll and the shoe.

3. In an ironer, a roll, a shoe, a frame at one end of the roll, a shoe supporting member hinged thereto, motor driven mechanism carried by the frame for driving the roll and for moving it toward and away from the shoe, a second member hinged to the frame, a pin slidably carried by said second member and movable into and out of engagement with the shoe supporting member for releasably coupling said members, and means including a spring arranged between the frame and said second member for limiting the pressure between the roll and the shoe.

4. In an ironer, a roll, a shoe, a frame at one end of the roll, a shoe supporting member hinged thereto, motor driven mechanism carried by the frame for driving the roll and for moving it toward and away from the shoe, a second member hinged to the frame, a pin slidably and rotatably carried in said second member for releasably coupling said members, cam means on the pin

operable upon rotation thereof for moving the pin axially to a position uncoupling said members, and a spring arranged between said second member and the frame for limiting the pressure between the roll and shoe.

5. In an ironer, a roll, a shoe, a frame at one end of the roll, a member hinged to the frame and having an arm supporting the shoe projecting therefrom, motor driven mechanism carried by said frame for driving the roll and for moving it toward and away from the shoe, a second member hinged to the frame, a pin slidably and rotatably carried in said second member for releasably coupling said members, cam means on the pin effective upon rotation thereof to move the pin axially to a position uncoupling said members, and a part on said pin arranged to engage said shoe supporting member and separate it from said second member upon rotation of the pin.

6. In an ironer, a roll, a shoe, mechanism for driving the roll and for effecting engagement and separation of the roll and shoe, a rod, means for supporting the shoe on the rod for pivotal movement about the axis of the rod, there being sufficient clearance in said supporting means to permit tilting of the shoe about an axis perpendicular to the rod, and means including cooperating cam surfaces on the shoe supporting means and the rod for resiliently centering the shoe on the rod.

7. In an ironer, a roll, a shoe, mechanism for driving the roll and for effecting engagement and separation of the roll and shoe, a rod, a sleeve on the rod pivotally supporting the shoe, there being sufficient clearance between the sleeve and the rod to permit tilting of the shoe about an axis perpendicular to the rod, and means including cooperating cam surfaces on the sleeve and the rod for resiliently centering the shoe on said rod.

8. In an ironer, cooperating ironing elements, mechanism for effecting engagement and separation of the ironing elements comprising a continuously rotating driving member, a driven member, a clutch member rotatable therewith, and means for effecting engagement of alternate ends of the clutch member with the driving member to establish a driving connection to the driven member.

9. In an ironer, cooperating ironing elements, mechanism for effecting engagement and separation of the ironing elements comprising a continuously rotating driving member, a driven member, a clutch member rotatable therewith, spring means for urging the clutch member into engagement with the driving member to establish a driving connection to the driven member, and provisions whereby the clutch member is urged out of engagement with the driving member by the spring means upon a predetermined rotation of the driven member.

10. In an ironer, cooperating ironing elements, mechanism for effecting engagement and separation of the ironing elements comprising a continuously rotating driving member, a driven member, a clutch member rotatable therewith, spring means for urging the clutch member into engagement with the driving member to establish a driving connection to the driven member, and a swivel connection between the spring

means and the clutch member whereby the clutch member is urged out of engagement with the driving member by the spring means upon a predetermined rotation of the driven member.

11. In an ironer, cooperating ironing elements, mechanism for effecting engagement and separation of the ironing elements comprising a continuously rotating driving member, a driven member, a clutch member rotatable therewith, spring means for urging alternate ends of the clutch member into engagement with the driving member to establish a driving connection to the driven member, a control member normally preventing movement of the clutch member to the driving position and movable to a position permitting movement of the clutch member to the driving position, and means carried by the control member for moving the clutch member from the driving position upon a predetermined rotation of the driven member.

12. In an ironer, cooperating ironing elements, mechanism for effecting engagement and separation of the ironing elements comprising a continuously rotating driving member, a driven member, a clutch member rotatable therewith, spring means for moving the clutch member into engagement with the driving member to establish a driving connection to the driven member, a control member normally preventing movement of the clutch member to the driving position and movable to a position permitting movement of the clutch member to the driving position, and means including said spring means for moving the clutch member from the driving position upon a predetermined rotation of the driven member.

13. In an ironer, cooperating ironing elements, mechanism for effecting engagement and separation of the ironing elements comprising a continuously rotating driving member, a driven member, a clutch member rotatable with the driven member, each end thereof being movable into engagement with the driving member to establish a driving connection to the driven member, and spring means for biasing the clutch member in a predetermined direction, the clutch member being rotatable relative to the spring means whereby during the rotation of the driven member alternate ends of the clutch member are biased to the driving position.

14. In an ironer, a driving gear, a roll, a driven gear carried by the roll, means for effecting relative movement of the gears into and out of mesh for controlling the rotation of the roll, and means including a flexible diaphragm extending transverse to the roll axis and flexible in the direction of its thickness providing a tiltable support for the roll whereby the driven gear may yield to prevent jamming as the gears are meshed.

15. In an ironer, a driving gear, a roll, a driven gear carried by the roll, means for effecting relative movement of the gears into and out of mesh for controlling the rotation of the roll, a roll bearing, and means including radial members flexible transverse to the length thereof between the roll and roll bearing providing a tiltable support for the roll whereby the driven gear may yield to prevent jamming as the gears are meshed.
